GANSE STEEL COMPANY, OF CHICAGO HEIGHTS, ILLINOIS, A CORPORATION OF
MAINE

CLOSING CHAIN

Application filed November 1, 1929. Serial No. 403,950.

This invention relates to improvements in the design of chain links and a method of making the same and principally to a method for constructing the improved links by casting from manganese steel.

A common design of chain which has been heretofore manufactured consists of a plurality of links, each of which is composed of a plurality of separately formed link parts generally comprising members of elliptical shape having a pair of spaced openings to receive the connecting link pins. The plurality of link parts are arranged in parallel positions so that their openings are aligned thus, if there are five link parts, the next adjacent link will be composed of four link parts so that the ends will be received in the spaces between the five link parts. It will be noted that the link pin is passed through the receiving openings of the connected links described, thus there will be nine bearing points serving to transmit the load imposed upon the chain. Thus if the spacing or alignment of the holes forming the link parts are not sufficiently accurate, certain of the bearing openings will receive a greater portion of the load thus resulting in deformation of the openings. It has been found especially difficult to provide perfect alignment of the openings when the separate parts are cast from manganese steel and a grinding operation has been required. The cost of such operation is prohibitive.

It is therefore the purpose of my invention to provide a chain of the type mentioned which may be manufactured of manganese steel without resulting in the objections mentioned above and my invention resides in casting the plurality of link parts constituting one link in a single unit by providing a narrow tie web between each of the parts. The casting so formed may be finished by broaching the aligned openings at each end of the casting in one operation, thus securing perfect alignment and providing a chain which will give increased wear in use.

My invention will be described in connection with the detail description of the links shown in the accompanying drawing.

Figure 1 is a plan view of a chain link

shown in association with a fixture for finishing with a broaching tool.

Figure 2 is a side view of an outside chain link.

Figure 3 is a side view of an inside chain link adapted to cooperate with the link shown in Figure 2.

Figure 4 is a plan view of an end connecting link, and

Figure 5 is a side view of the link shown in Figure 4.

The present invention is concerned with the development of a heavy duty warping chain, which in former practice has been made up by providing a plurality of parallelly disposed cast link parts which are connected to adjacent groups of link parts by means of connecting link pins. If the openings which are formed in the individual link parts are not equally spaced, there will be an uneven loading and furthermore a strain is placed upon the heads of the link pins. According to the present invention each group of link parts instead of being separately cast are cast together as a unit by providing small tying webs between the individual link parts. Each of the units so cast may have the openings at each end broached in a single operation, in order to uniformly align the holes.

One form of the improved link unit is illustrated in plan in Figure 1, which may be either the outside or inside link unit, the side elevation of an outside link being illustrated in Figure 2, and the side elevation of an inside link unit being illustrated in Figure 3. The construction comprises a plurality of plates 1, 2, 3 and 4 which are formed with an eye in each end, cored openings 5 being formed at one end and cored openings 6 being provided at the opposite end. The plates are connected by a web generally designated 7 which includes portions 8, 9 and 10 between the plates. This web is relatively narrow with respect to the length of the link plates and may have a form in section such as shown in Figures 2 and 3 in which the narrowest part is at the center portion of the link and the web

widens out towards the top and bottom of the link.

Figures 4 and 5 illustrate an end connecting link which is curved in such a manner that the chain will be started rolling over the cam in a proper manner. This link unit is designated 40 and has eye portions 41 and knuckles 42 at the opposite ends. The knuckles 42 instead of being in alignment with the outer eye portions at the opposite end are spread closer together in this case and have a width equal to two of the eye portions. The lower part of the link unit 40 is curved as at 43 for the purpose described. Aligned openings 44 are formed at one end and 45 at the other.

It will be understood that various modified forms of link units may be designed, all of which essentially comprise a plurality of load transmitting portions formed with a plurality of aligned openings. It will be apparent that casting such units will not result in perfect alignment of the openings and therefore in order to finish the holes or openings to the correct sizes and alignment, it is preferable that a broaching operation be performed upon each integrally cast link unit. Figure 1 illustrates the manner of carrying out a broaching operation in which a fixture 50 is provided to receive a link unit which is held at one end by the locating pin 51 passed through the aligned openings. The openings at the other end of the link unit may then be broached by passing the broaching tool 52 through the openings. It will be apparent that such a method will result in perfect alignment of the link pin receiving openings. Therefore when such a link is assembled, the load transmitting ears or eye portions will receive equal portions of the load and further the provision of the tying webs will eliminate the strain which might otherwise fall upon the heads of the connecting link pins.

Although I have described in detail certain preferred forms of link units, it will be apparent that many variations may be resorted to without departing from the spirit of my invention as expressed in the appended claims.

I claim:

1. An articulated chain composed of a plurality of pivotally-connected links, each of said links comprising an integral casting of manganese steel formed to consist of a plurality of parallelly-disposed link plates, each of which has a thickness materially less than the length of said plates, said plates being spaced apart substantially equal to the thickness of the individual plates by transverse webs extending centrally therebetween, said webs being relatively narrow in a direction lengthwise of the link and said link plates having aligned openings at each end adapted to receive link pins for pivotally connecting adjacent links.

2. An articulated chain composed of a plurality of pivotally connected links, each of said links comprising an integral casting of manganese steel forming a plurality of relatively narrow link plates having curved ends spaced apart substantially equal to the thickness of the individual plates by transverse webs extending centrally therebetween, said transverse webs being substantially narrow in a direction lengthwise of the link and decreasing in thickness from the upper and lower sides of the link towards the central portion thereof, said link plates having aligned transverse openings at each end adapted to receive link pins for pivotal connection of adjacent links.

Signed at Chicago Heights, Illinois, this 29th day of October, 1929.

CLAUDE RORABECK.
